UNITED STATES PATENT OFFICE.

FRANK L. GORMLEY, OF BROOKLINE, MASSACHUSETTS, ASSIGNOR TO THE BUDA COMPANY, OF HARVEY, ILLINOIS, A CORPORATION OF ILLINOIS.

HIGH-SPEED LIFTING JACK.

Application filed May 15, 1925. Serial No. 30,420.

To all whom it may concern:

Be it known that I, FRANK L. GORMLEY, a citizen of the United States of America, and a resident of Brookline, in the county 5 of Norfolk, in the State of Massachusetts, have invented certain new and useful Improvements in High-Speed Lifting Jacks, of which the following is a specification.

This invention relates to high speed self-lowering lifting jacks and has for its object 10 the production of a simple but effective and strong and durable jack of this character in which is provided a novel means for controlling the lowering of the load and for preventing back lash of the load during the 15 lifting operation.

These objects are attained by the mechanism illustrated in the accompanying drawings.

20 For the purpose of illustrating the invention, one preferred form thereof is illustrated in the drawings, this form having been found to give satisfactory and reliable results, although it is to be understood that 25 the various instrumentalities of which the invention consists can be variously arranged and organized, and the invention is not limited to the precise arrangement and organization of these instrumentalities as 30 herein shown and described except as required by the scope of the appended claims.

Of the drawings:

Figure 1 represents a vertical section of 35 a lifting jack embodying the principles of the present invention.

Figure 2 represents a horizontal plan on line 2, 2, on Fig. 1.

Figure 3 represents a horizontal plan on 40 line 2, 2, on Fig. 1 of a portion of the lifting jack with the cover plate removed.

Figure 4 represents a vertical section on line 4, 4, on Fig. 2.

Figure 5 represents a vertical section on line 5, 5, on Fig. 2, and

45 Figure 6 represents a vertical section on line 6, 6, on Fig. 4.

Similar characters indicate like parts throughout the several figures of the drawings.

50 In the drawings, 10 is the base of a lifting jack having an upwardly extending projection 11, to which is threaded the lower end of a standard 12, in the upper end of which is a cylindrical bearing 13 for the vertically movable ram 14.

This ram 14 has an enlarged head 15 adapted to rest upon the upper end of the standard 12 when in its lowest position.

The lower end of the ram 14 has mounted therein a nut 16 threaded to the main lifting screw 17, the lower end of which has keyed thereto a bevel gear 18 meshing with a bevel gear 19 formed upon the actuating shaft 20.

The shaft 20 has mounted on its outer end 65 a device 21 for imparting rotary movement to the shaft 20 in one direction only, and that is, during the lifting operation.

This actuating device 21 may be of any well known construction and therefore is 70 not shown or described in detail.

The standard 12 has a lateral extension 22, one vertical wall of which has a bearing 23 therein, in which said actuating shaft 20 is mounted.

In the chamber formed by this lateral extension 22 is mounted a worm gear 24 keyed to the actuating shaft 20 and meshing with a worm 25 formed upon the horizontal shaft 26.

The pitch of the thread of said worm 25 is such as to permit it to be rotated by said worm gear 24 in whichever direction the gear 24 may be rotated.

Surrounding the hub of the gear 18 is a 85 bearing plate 27 having a groove in its under face into which extend the anti-frictional members 28 resting upon another bearing plate 29 supported and centrally disposed upon the projection 11 of the 90 base 10.

One end of the worm shaft 26 is mounted in a bearing in the wall of the extension 22, while the opposite end is mounted in a bearing in a removable disk 30, threaded to the 95 opposite wall of said extension.

Thrust bearings 31 and 32 are provided at the opposite ends of the worm shaft 26.

Keyed to the shaft 26 is an annular member 33 having loosely mounted thereon a worm gear 34 provided with an annular flange 35 having secured therein a ratchet 36.

The member 33 has a flange 37 at one end thereof on which is pivotally mounted a plurality of pawls 38, normally forced outwardly by springs 39 into engagement with the teeth of the ratchet 36.

The worm gear 34 coacts with a vertical worm 39 formed upon the shaft 40.

This shaft 40 has a bearing 41 in the lower wall of the extension 22 and another bearing 42 in the partition or wall 43 near the upper end of said extension.

5 Between the under face of the extension 43 and the shoulder 44 on the worm 39 is a thrust bearing 45.

The upper end of the shaft 40 has keyed thereto a disk 46 having pivotally mounted thereon at 47 a plurality of bearing plates 48, normally forced outwardly by springs 49, against the brake arms 50 surrounding the disk 46 and bearing plates 48, said brake arms 50 being pivoted at one end at 51 to 15 the wall 43.

The opposite ends of the brake arms 50 are provided with parallel, separated extensions 52, between which is positioned a cam member 53 mounted upon a pin 54 extending 20 upwardly through the cover plate 55 and having an actuating finger 56 secured to its upper end.

The partition or wall 43 has extending upwardly therefrom lugs 57 between which and 25 the extensions 52 are disposed helical springs 58 which normally retain the brake arms 50 in contact with the bearing plates 48 pivotally mounted upon the disk 46.

When the parts are in the position indicated in the drawings there will be sufficient friction between the brake arms 50 and the bearing plates 48 to retain the ram in elevated position and prevent its lowering under the load. During a lifting or elevating operation, the worm 39 and worm wheel 34 are held by the brake against movement while the worm 25 is driven by the worm wheel 24 and the pawls 38 run idly over the teeth of the ratchet 36 in a clock-wise direction, viewing Fig. 6. Between successive upward movements of the ram, lowering movement thereof is prevented by engagement of the pawls 38 with the teeth of the stationary ratchet 36. The speed multiplying ratio between the worm gear 24 and the worm 25 causes the pawls to become immediately engaged with the ratchet teeth thereby through the worm 25, shaft 20, and connecting gears, locking the ram against 40 lowering before any perceptible retrograde movement can occur. Back lash of the ram which is very undesirable and extremely dangerous, particularly in heavy duty jacks is therefore effectually prevented. By this 45 construction, excessive strain on the pawls and ratchet teeth is obviated; both the pawls and teeth are permitted to be made of substantial dimensions affording adequate strength, and a plurality of pawls are enabled to be simultaneously engaged with the ratchet teeth, and even in the event of breakage or accident the ram will be prevented from abrupt lowering by the retarding action of the worm 25 alone.

60 When it is desired to lower the load the

operator manipulates the finger 56 causing the cam 53 to separate the brake arms 50, thereby reducing the frictional contact between these arms and the bearing plates 48.

It is obvious that by the movement of the 70 finger 56 about the axis of the pin 54 any degree of friction between the arms 50 and plates 48 may be secured and the speed of lowering the ram controlled.

The extension 22 is formed integral with 75 the standard 12 and the partition or wall 43 is also formed integral therewith, this wall being somewhat depressed and forming a chamber 59 in which the speed controlling devices 46, 48, 50, and 53, are positioned, 80 this chamber being closed by means of the cover plate 55.

The bearing 23 is provided with a bushing 60 and the shaft 20 may be installed in the bearing 23 from the inner end thereof before the bushing 60 is inserted into the outer end thereof, the said shaft being inserted into the chamber within the extension 22 through the opening in the bottom of the standard 12 before said standard has been 90 threaded to the base 10.

The bushing is then positioned within the bearing 23 and around the shaft 20 and then the actuating device 21 is installed on the outer end of said shaft.

95 It will be noted that in the present construction all of the gears and worms are revoluble in bearings formed in a single unitary shell, casing or standard, thereby dispensing with the cover plates generally used 100 in lifting jacks of this character.

Heretofore, when some of the parts were mounted upon the cover plate secured to the standard or casing by means of screws, the latter would sometimes become loose 105 and allow the cover plate to shift, thus moving out of alignment the gears for lifting the load. This movement of the gears out of alignment would cause the binding of the teeth and interfere with the proper working of the jack.

110 By forming all the bearings for these working parts in a single casing, this objection is wholly overcome.

The worm gear 24 and the worm 25 rotate both when the ram is being raised and also when it is being lowered.

115 When the load is being lifted the worm 39 and worm gear 34 are prevented from being rotated by means of the braking mechanism 120 46, 48 and 50.

This makes a very simple form of self-lowering speed controlled lifting jack, all of the weight of which is in the lower end thereof, which lower end is provided with a broad base, giving the jack a very firm support when in use.

125 By this construction it makes it possible to form all of the bearings for the working parts in a single integral shell or casing,

thereby preventing any of the working parts from getting out of alignment which is obviously a great advantage.

It is believed that the operation and many advantages of the invention will be understood without further description.

Having thus described my invention, I claim—

1. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a worm driven thereby; means for rotating said driving gear and worm gear; an annular member secured to said worm shaft; pawls carried thereby; a worm pinion surrounding said annular member and carrying a ratchet coacting with said pawls; a vertical shaft having a worm thread meshing with said pinion; a disk secured to the upper end of said vertical shaft; brake members pivoted to said disk; two brake arms surrounding said disk and with which said members coact; springs for normally retaining said arms and members in engagement; and a cam member adapted to be moved to separate said arms. 70
2. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a horizontally disposed worm driven thereby; means for rotating said driving gear and worm gear; a vertically disposed worm; means interposed between said worms for 75 rotating the vertical worm in one direction only; a disk secured to the upper end of said vertical shaft; brake members pivoted to said disk; two brake arms surrounding said disk and with which said members coact; springs for normally retaining said arms and members in engagement; and a cam member adapted to be moved to separate said arms. 80
3. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a horizontally disposed worm driven thereby; means for rotating said driving gear and worm gear; a vertically disposed worm; means interposed between said worms for 85 rotating the vertical worm in one direction only by the horizontal worm when rotated during the lowering of the load; a disk secured to the upper end of said vertical shaft; brake members pivoted to said disk; two brake arms surrounding said disk and with which said members coact; springs for normally retaining said arms and members in engagement; and a cam member adapted to be moved to separate said arms. 90
4. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a worm driven thereby; manually actuated means for rotating said driving gear and worm gear in one direction only; an annular member secured to said worm shaft; pawls carried thereby; a worm pinion surrounding said annular member and carrying a ratchet coacting with said pawls; a vertical shaft having a worm thread meshing with said pinion; a disk secured to the upper end of said vertical shaft; brake members pivoted to said disk; two brake arms surrounding said disk and with which said members coact; springs for normally retaining said arms and members in engagement; and a cam member adapted to be moved to separate said arms. 95
5. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a worm beneath said worm gear and driven thereby; means for rotating said driving gear and worm gear in one direction to raise the ram; an annular member secured to said worm shaft; pawls carried thereby; a worm pinion surrounding said annular member and carrying a ratchet the teeth of which are adapted to engage with said pawls during the lowering of the load; a vertical shaft having a worm thread meshing with said pinion; and means at the upper end of said vertical shaft for controlling its rotation. 100
6. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a horizontally disposed worm rotated thereby; means for rotating said driving gear and worm gear; a vertically disposed worm; means interposed between said worms for 105 rotating the vertical worm in one direction only by the horizontal worm when rotated during the lowering of the load; a disk secured to the upper end of said vertical shaft; brake members pivoted to said disk; two brake arms surrounding said disk and with which said members coact; springs for normally retaining said arms and members in engagement; and a cam member adapted to be moved to separate said arms. 110
7. In a self-lowering lifting jack; a standard; a ram reciprocable in said standard; means for raising the ram including a driving shaft; a worm gear secured to the driving shaft; a horizontally disposed worm driven by said worm gear during its rotation in either direction; a vertically disposed worm; means interposed between said worms for rotating the vertical worm in one direction only by the rotation of the horizontal worm during the lowering of the load; and means at the upper end of the vertical worm for controlling its rotation. 115
8. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a worm driven thereby; manually actuated means for rotating said driving gear and worm gear in one direction only; an annular member secured to said worm shaft; pawls carried thereby; a worm pinion surrounding said annular member and carrying a ratchet coacting with said pawls; a vertical shaft having a worm thread meshing with said pinion; a disk secured to the upper end of said vertical shaft; brake members pivoted to said disk; two brake arms surrounding said disk and with which said members coact; springs for normally retaining said arms and members in engagement; and a cam member adapted to be moved to separate said arms. 120
9. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a worm driven thereby; manually actuated means for rotating said driving gear and worm gear in one direction only; an annular member secured to said worm shaft; pawls carried thereby; a worm pinion surrounding said annular member and carrying a ratchet coacting with said pawls; a vertical shaft having a worm thread meshing with said pinion; a disk secured to the upper end of said vertical shaft; brake members pivoted to said disk; two brake arms surrounding said disk and with which said members coact; springs for normally retaining said arms and members in engagement; and a cam member adapted to be moved to separate said arms. 125
10. In a self-lowering lifting jack; a standard; a ram reciprocable in said standard; a nut in said ram; a rotatable screw in said nut; a gear on the lower end of said screw; a driving gear meshing therewith; a worm gear secured to the driving gear shaft; a worm driven thereby; manually actuated means for rotating said driving gear and worm gear in one direction only; an annular member secured to said worm shaft; pawls carried thereby; a worm pinion surrounding said annular member and carrying a ratchet coacting with said pawls; a vertical shaft having a worm thread meshing with said pinion; a disk secured to the upper end of said vertical shaft; brake members pivoted to said disk; two brake arms surrounding said disk and with which said members coact; springs for normally retaining said arms and members in engagement; and a cam member adapted to be moved to separate said arms. 130

8. In a self-lowering lifting jack; a standard; a ram reciprocable in said standard; means for raising the ram including a driving shaft; a worm gear secured to the driving shaft; a worm driven by the worm gear during its rotation in either direction; a member secured to said worm shaft; pawls carried thereby; a worm pinion surrounding said member and carrying a ratchet coacting with said pawls; a vertical shaft having a worm thread meshing with said pinion; a disk secured to the upper end of said vertical shaft; brake members pivoted to said disk; two brake arms surrounding said disk and with which said members coact; springs for normally retaining said arms and members in engagement; and a cam member adapted to be moved to separate said arms.

9. In a self-lowering lifting jack; a standard; a ram reciprocable in said standard; means for raising the ram including a driving shaft; a worm gear secured to the driving shaft; a worm driven by said worm gear during its rotation in either direction; a member secured to said worm shaft; pawls carried thereby; a worm pinion surrounding said member and carrying a ratchet in engagement with said pawls during the lowering of the load; a vertical shaft having a worm thread meshing with said pinion and rotated thereby in one direction only; a disk secured to the upper end of said vertical shaft; brake members pivoted to said disk; two brake arms surrounding said disk and with which said members coact; springs for normally retaining said arms and members in engagement; and a cam member adapted to be moved to separate said arms.

10. In a self-lowering lifting jack; a standard including a base removably mounted in the lower end of said standard; a vertically movable ram in said standard; rotatable means within said standard and chamber for raising the ram, a driving shaft; a worm gear secured to said driving shaft; a horizontally disposed worm in mesh with said worm gear; a vertically disposed worm; means actuated by said horizontal worm when rotated by the lowering of the load for imparting rotary movement to the vertical worm; and means at the upper end of the vertical worm for controlling its speed during the lowering of the load.

11. In a self-lowering lifting jack; a standard including a chamber in a lateral extension formed integral therewith; a base to which the lower end of said standard is threaded; a vertically movable ram in said standard; rotatable means within said standard and chamber for raising the ram and including a horizontal worm having a bearing for one end in one wall of said extension; a disk threaded to said extension and having a bearing for the opposite end of said worm; means at the upper end of the

vertical worm for controlling its speed during the lowering of the load; and means interposed between two worms for rotating the vertical worm only during the lowering.

12. In a self-lowering lifting jack; a standard having a chamber at one side of its lower end; a ram reciprocable in said standard; a nut in said ram; a rotatable screw in said nut; a gear on the lower end of said screw; a driving gear meshing therewith; a worm gear secured to the driving gear shaft and positioned within said chamber; a worm within said chamber and driven by said worm gear; means for rotating said driving gear and worm gear; an annular member secured to said worm shaft; pawls carried thereby; a worm pinion surrounding said annular member and carrying a ratchet coacting with said pawls; a vertical shaft having a worm thread meshing with said pinion; a disk secured to the upper end of said vertical shaft; brake members pivoted to said disk; two brake arms surrounding said disk and with which said members coact; springs for normally retaining said arms and members in engagement; and a cam member adapted to be moved to separate said arms.

13. In a self-lowering lifting jack including a vertically movable ram; a standard having a chamber in a lateral extension formed integral therewith; a base to which the lower end of said standard is threaded; rotatable means within said standard and chamber for raising the ram and including a driving shaft; a worm gear secured to said driving shaft; a worm meshing with said gear; a vertical shaft adapted to be rotated by said worm only during the lowering of the ram under the load; and braking mechanism at the upper end of said vertical shaft for controlling the speed of lowering.

14. In a self-lowering lifting jack including a vertically movable ram; a standard having a chamber in a lateral extension formed integral therewith; a base to which the lower end of said standard is threaded; rotatable means within said standard and chamber for raising the ram and including a driving shaft; a worm gear secured to said driving shaft; a worm meshing with said gear; a vertical shaft adapted to be rotated by said worm only during the lowering of the ram under the load, said means being rotatable in bearings formed in the walls of said standard and extension thereof; and braking mechanism at the upper end of said vertical shaft for controlling the speed of lowering.

15. In a self-lowering lifting jack including a vertically movable ram; a standard having a chamber in a lateral extension formed integral therewith; a base to which the lower end of said standard is threaded; rotatable means within said standard and

- chamber for raising the ram and including a driving shaft; a worm gear secured to said driving shaft; a worm meshing with said gear; a vertical shaft adapted to be 5 cured to the upper end of said vertical shaft 65 and adapted to be frictionally engaged to control the speed of lowering.
5. In a self-lowering lifting jack including a vertically movable ram; a standard; a base for the lower end of said standard 70 having a lateral extension with a chamber therein communicating with the interior of said standard; rotatable means within said standard and chamber for raising the ram and including a driving shaft; a driving 75 member thereon; a vertical shaft adapted to be rotated only during the lowering of the ram under the load; braking mechanism including in part a rotatable disk secured to the upper end of said vertical shaft and 80 adapted to be frictionally engaged to control the speed of lowering, said mechanism being confined within a recess at the top of said extension and also including two 85 brake arms coacting with said disk; a plate 85 covering said recess; and a manually actuated cam member on said plate for separating said arms.
16. In a self-lowering lifting jack, a standard; a vertically movable ram therein; means within said standard for raising said ram including a driving shaft; a driving 15 member thereon; a horizontal shaft adapted to rotate with said driving member, a vertical worm; a member rotatable with said horizontal shaft carrying a plurality of pawls; a worm gear loosely mounted 20 upon said horizontal shaft member meshing with and adapted to rotate said worm; said gear being provided with a ratchet coacting with said pawls; and means at the upper end of said vertical worm for controlling 25 the speed of its rotation.
17. In a self-lowering lifting jack, a standard; a vertically movable ram therein; means within said standard for raising said ram including a driving shaft; a driving 30 member thereon; a horizontal shaft adapted to rotate with said driving shaft; a vertical worm; a member rotatable with said horizontal shaft carrying a plurality of pawls; a worm gear loosely mounted upon 35 said horizontal shaft member meshing with and adapted to drive said worm, said gear being provided with an annular flange; a ratchet secured within said flange and coacting with said pawls; and means at the 40 upper end of said worm for controlling the speed of its rotation.
18. In a self-lowering lifting jack including a vertically movable ram; a standard; a base for said standard; rotatable means 45 within said standard for raising the ram and including a driving shaft; a driving member thereon; a vertical shaft adapted to be rotated only during the lowering of the ram under the load; and braking mechanism 50 including in part a rotatable disk secured to the upper end of said vertical shaft and adapted to be frictionally engaged to control the speed of lowering.
19. In a self-lowering lifting jack including a vertically movable ram; a standard; a base for the lower end of said standard; rotatable means within said standard for raising the ram and including a driving shaft; a driving member thereon; a vertical shaft 55 adapted to be rotated only during the lowering of the ram under the load, said shafts being rotatable in bearings formed in the walls of said standard; and braking mechanism including in part a rotatable disk se- 60 cured to the upper end of said vertical shaft 65 and adapted to be frictionally engaged to control the speed of lowering.
20. In a self-lowering lifting jack including a vertically movable ram; a standard; a base for the lower end of said standard 70 having a lateral extension with a chamber therein communicating with the interior of said standard; rotatable means within said standard and chamber for raising the ram and including a driving shaft; a driving 75 member thereon; a vertical shaft adapted to be rotated only during the lowering of the ram under the load; braking mechanism including in part a rotatable disk secured to the upper end of said vertical shaft and 80 adapted to be frictionally engaged to control the speed of lowering, said mechanism being confined within a recess at the top of said extension and also including two 85 brake arms coacting with said disk; a plate 85 covering said recess; and a manually actuated cam member on said plate for separating said arms.
21. In a self-lowering lifting jack; a standard; a vertically movable ram therein; means within said standard for raising said ram including a driving shaft; a driving member thereon; a horizontal shaft rotatable with said driving member; a vertical worm; a member rotatable with said horizontal shaft carrying a plurality of pawls; a worm gear loosely mounted upon 90 said horizontal shaft member meshing with and adapted to drive said worm, said gear being provided with a ratchet coacting with said 95 pawls; means at the upper end of said worm for controlling the speed of its rotation; and a manually actuated cam member for regulating 100 said controlling means.
22. In a self-lowering lifting jack; a standard; a vertically movable ram therein; means within said standard for raising said ram including a driving shaft; a driving member thereon; a horizontal shaft rotatable with said driving member; a vertical worm; a member rotatable with said horizontal shaft carrying a plurality of pawls; a worm gear loosely mounted upon 110 said horizontal shaft member meshing with and adapted to drive said worm, said gear being provided with an annular flange; a ratchet secured within said flange and coacting with 115 said pawls; means at the upper end of said worm for controlling the speed of its rotation, said means including two pivoted 120 brake arms; a cam between said arms adapted to be moved to separate said arms; and a lever for actuating said cam.
23. In a self-lowering lifting jack, a standard; a ram movable relatively thereto; actuating means for raising the ram including a driving shaft rotatable in both directions; a worm gear keyed to said shaft; a 125

worm adapted to be rotated by the rotation of said gear in either direction; a second worm vertically disposed and adapted to be rotated by the first mentioned worm in one direction only during the lowering of the ram under the load; a disk secured to and rotatable with said second worm; brake members carried thereby; and brake arms surrounding said disk and with which said 10 brake members coact to control the speed of rotation of said disk.

24. In a self-lowering lifting jack, a standard; a ram movable relatively thereto; actuating means for raising the ram including a driving shaft rotatable in both directions; a worm gear keyed to said shaft; a worm adapted to be rotated by the rotation of said gear in either direction; a second worm vertically disposed and adapted to be 15 rotated by the first mentioned worm in one direction only during the lowering of the ram under the load; a disk secured to and rotatable with said second worm; brake members pivoted thereto; pivoted brake 20 arms surrounding said disk and with which said members are in frictional contact; and 25

means manually actuated for separating said arms.

25. A lifting jack comprising a lifting ram, a rotatable shaft for actuating said ram, a brake, and means interposed between said brake and said shaft including a worm connected to the brake, a worm connected to the shaft, and a one-way clutch forming an operative connection between said worms, 30 for preventing back lash of the ram during the lifting operation and controlling the downward movement of the ram during the lowering operation.

26. A lifting jack comprising a lifting ram, a rotatable shaft for actuating the ram, a manually controlled brake, a plurality of worms, one being positively connected to and rotatable in either direction by said shaft, and the other being connected with and controlled in its rotation by said brake, and a one-way driving connection interposed 40 between said worms.

Signed by me at Harvey, Ill., this 12th day of May, 1925.

FRANK L. GORMLEY.
